UNITED STATES PATENT OFFICE.

HENNING R. SJOLANDER, OF ISHPEMING, MICHIGAN.

ELECTRIC-CIRCUIT TESTER.

1,315,531.

Specification of Letters Patent.

Patented Sept. 9, 1919.

Application filed February 12, 1919. Serial No. 276,590.

To all whom it may concern:

Be it known that I, HENNING R. SJOLANDER, a citizen of the United States, residing at Ishpeming, in the county of Marquette and State of Michigan, have invented 5 certain new and useful Improvements in Electric-Circuit Testers, of which the following is a specification, reference being had to the accompanying drawings, forming a 10 part thereof.

This invention relates to means for testing a plurality of associated electric circuits especially when they are arranged with a common return or ground connection as in the 15 case of the ignition circuit of an automobile or any multiple cylinder internal combustion engine. The invention provides means enabling the driver or engineer to determine at any time whether the spark plugs and the 20 like of the several cylinders are in good working condition, and to detect and locate a fault in any one of such spark plugs or other ignition devices by cutting out of operation all the cylinders but one, and selecting 25 any such one to be run alone for observing its operation or noting any defect of operation apart from the remainder. The invention consists in the elements and features of construction and their combination herein- 30 after described and shown in the drawings as indicated by the claims.

In the drawings:

Figure 1 is a face view of an instrument embodying this invention.

Fig. 2 is a section taken as indicated at 35 line 2-2 on Fig. 1.

Fig. 3 is a face view of the insulating mount in which the electrodes forming indicating spark gaps are carried.

Fig. 4 is a rear face view of the cover or shield member provided with apertures for disclosing the indicating sparks in the spark gaps.

Fig. 5 is a detail section taken as indicated 45 at line 5-5 on Figure 1.

Fig. 6 is a detail section taken similarly to Fig. 5 but showing the parts differently adjusted so that the aperture or window of the shield or cover member is out of registration with the spark gaps.

Fig. 7 is a detail section taken as indicated 50 at line 7-7 on Fig. 1.

Fig. 8 is a wiring diagram for the device embodying this invention.

As illustrated in the drawings this device 55 is particularly designed for use with an internal combustion engine and such use is suggested by the wiring diagram on Fig. 8; but it may be understood that the principles involved will apply equally well to a circuit 60 tester especially arranged for some other electrical devices. The structure illustrated consists of a base or mount, A, of insulating material in which there are secured a plurality of pairs of electrodes, B and C, provided at the rear side of the mount, A, with connector sleeves, B¹ and C¹, respectively, to receive wires, D, of the various circuits to be tested. As applied to an internal combustion engine, each pair of electrodes, B and C, is 65 connected in series with one of the spark plugs of an engine, preferably in the line running from the distributor indicated in Fig. 8 at E to the spark plugs, each of which is denoted by the letter, F, in said 70 diagram. Thus, when the engine is running properly, there will be a spark formed between each pair of electrodes, B and C, simultaneously with the firing of the particular cylinder whose spark plug is connected in series with a pair of electrodes, 75 and the presence of such energy-indicating spark between these electrodes will advise the engineer or driver that the circuit at least is complete from the distributor to the 80 spark plug.

However, if it should happen that the spark plug of any cylinder has become fouled with soot or oil, or otherwise short-circuited, the cylinder would not fire properly, although the current would pass 85 from the distributor to the spark plug and would be so indicated between electrodes, B and C, of that line. For detecting such faults of the spark plugs, therefore, another method 90 is adopted, namely the grounding of all the spark plugs but one, selecting various groupings of the plugs in this way, thus causing the engine to run on one cylinder alone until the faulty cylinder is definitely located.

The mount, A, is shown in the drawings as a circular disk and the shield or cover, G, is provided for it, also in the form of a circular disk, having a series of apertures ar-

ranged to register with the pairs of electrodes, B and C, so as to serve as sight windows through which the sparks at such electrodes may be observed, and each of these 5 apertures is lined with a metallic tube, H, having at its outer end a contact lug, H¹, extending radially inward from the sight aperture or window formed by the tube, H. At the other end of each tube, H, a contact 10 lug, H², extends in circumferential direction on the rear face of the cover member, G, for electrical contact with one of the electrodes in the base or mount, A. By this means each spark plug circuit is provided with a 15 contact, H¹, on the face of the cover member, G, over which there is rotatively mounted a multiple armed contact member, J, electrically connected through its pivot, K, with a ground wire, L, leading to the same 20 common return or ground connection, which is provided for the spark plug circuit.

The member, J, has a number of radial arms, J¹, each extending for engagement with one of the contact lugs, H¹, but numbering one less than the total number of such lugs, H¹, so that, at any time, the member, J, may serve to ground all of the spark plug circuits except one. By rotation upon its pivot, K, which is centrally located with respect to the circular arrangement of the contacts, H¹, each of said contacts in turn may be left ungrounded leaving the engine to operate upon the spark plug connected to such ungrounded contact, H¹, and permitting the engineer to observe the action of each cylinder individually. Each of the windows formed by the tubes, H, may have associated with it on the face of the cover member, G, a numeral corresponding to a 30 particular cylinder of the engine, to which the wires leading from electrodes B and C, are connected, and, if desired, the rotatable grounding member, J, may carry in place of its omitted contact arm, a small pointer or 35 arrow, M, which will call attention to the window and the numeral associated therewith indicating the particular cylinder being tested for any adjusted position of the grounding member. For throwing the device out of use, said grounding member, J, may be set at any intermediate position with its arms, J¹, extending into the spaces between adjacent contacts, H¹, so as to form no 40 electrical connection therewith. If desired, 45 the cover member, G, may also be rotatable upon the pivot, K, through a short range for moving its windows, formed by the tube, H, out of registration with the spark gaps. If the device is mounted on the dash board or 50 instrument board of an automobile, it may be preferable not to have the spark gaps in operation, tending to distract the driver's attention when the car is actually running. When the spark gaps are cut out of use by 55 limited rotation of the cover member, G, the

contact lugs or plates H², on the rear face of said shield or cover, will extend in engagement with both electrodes, B and C, of each pair, thus short-circuiting or shunting each spark gap and eliminating the spark 70 therein so long as this metallic circuit is provided by such positioning of the cover plate, G. For retaining said cover at either limit of movement, a spring detent, N, may be set in the face of the mount, A, as indicated in 75 Figs. 3, 4 and 7, engaging depressions, O and P, respectively at opposite ends of the groove, Q, which represents the range of such rotative adjustment of the cover.

The grounding member, J, being of more 80 or less resilient material with its central portion spaced away from the shield or cover member, G, and retained under the head of the pivot member, K, will provide sufficient pressure for good electrical contact between 85 each of its arms, J¹, and the lugs, H¹, and at the same time press the shield or cover, G, against the base or mount, A, insuring good contact of the lugs, H², with one or both of electrodes, B and C, of each pair. By reason 90 of its resilience, the grounding member, J, frictionally engages the surface of the shield or cover, G, and also the contacts, H¹, and the initial rotation of said grounding member for engagement with said contacts will 95 cause the limited rotation of the shield, G, required for moving its apertures into registration with the spark gaps at electrodes, B and C. Continued rotary adjustment of the member, J, in the same direction will 100 cause no further rotation of the shield after engagement of its detent, N, with depression, O, but when the member, J, has been successively adjusted for testing all the cylinders, a slight reverse movement of said member 105 sufficient to carry its arms out of contact with the lugs, H¹, and into registration with the spaces between them will also shift the shield, G, to position for covering the spark gaps, with shunt plates, H², bridging them 110 and with the detent, N, in depression, P.

I claim:

1. In combination with a plurality of electric circuits having a common return or "ground" connection, a testing device comprising an insulated mount carrying a series of contacts respectively wired to the individual circuits, and a grounded contact member formed to engage simultaneously a definite number but not all of said contacts, said 115 contact member and the carrying mount being relatively adjustable for selectively grounding said circuits in different groups to permit observing the operation of the remainder and detecting faults therein. 120

2. In the combination set out in claim 1, said grounded contact member being also adjustable out of engagement with all the contacts simultaneously to allow normal operation of the circuits. 125

3. In the combination set out in claim 1, said contacts being symmetrically disposed upon the carrying mount about an axis and the relative adjustment of the mount and the contact member being a rotation about such axis.
4. In the combination set out in claim 1, said contacts being arranged in a circle on the face of the mount and the grounded member being pivoted at the center of the circle.
5. In the combination set out in claim 1, said contacts being arranged in a circle on the face of the mount and the grounded member being pivoted at the center of the circle and having contact arms numbering one less than the contacts on said mount, whereby rotative adjustment of said member upon its pivot will ground any selected group of said circuits omitting one.
6. In combination with a plurality of electric circuits having a common return or ground connection; a testing device comprising a series of spaced visible indicators, each connected in series with one of said circuits, a shield or cover formed with a series of apertures spaced to register with said indicators respectively, the shield being mounted for limited bodily movement for shifting its apertures into such registration and disclosing the indicators, together with a series of spaced contacts on the cover, each connected to one of the circuits and a grounded contact member having a plurality of arms spaced for simultaneous engagement with the said contacts or with the spaces between them and mounted for movement over said shield or cover in frictional engagement therewith, whereby an initial movement of said grounded member will carry said apertures into registration with the indicators.
7. In the combination set out in claim 6, said series of indicators being disposed in circular arrangement with the shield or cover provided with apertures and contacts both located in circles concentric with that of the indicators, the grounded member and the shield being both mounted for rotative adjustment about the common axis of said circles.
8. In combination with a plurality of electric circuits having a common return or ground connection, a testing device comprising a series of contacts, respectively wired to the individual circuits, a manually operable member and grounded contact means actuated thereby for simultaneously engaging a definite number, but not all, of said series of contacts, said member being adjustable for thus grounding the individual circuits in different groups, to permit observing the remainder in operation for locating faults therein.
9. In the combination set out in claim 1, said contacts being circularly disposed on the mount with spaces between adjacent contacts and the contact member having arms numbering one less than said contacts and radiating from the center of such circular arrangement, spaced for simultaneous engagement of each arm with one of the contacts, and rotatively adjustable at will about the center for registering the arms with any group of contacts omitting one, or for registration of all the arms with the spaces between contacts.
10. In combination with a plurality of electric circuits, a testing device comprising a series of visible indicators, each connected in series with one of said circuits, a cover member or shield having a series of apertures through each of which one of said indicators is visible, the shield being movable for shifting said apertures out of registration with the indicators, each indicator having a pair of contacts connected to its incoming and outgoing leads respectively, and a shunt plate on the shield member for each pair of such contacts positioned to engage them when the shield apertures are moved out of registration with the indicators.
11. In combination with an internal combustion engine, a testing device for the ignition comprising a series of electrodes in pairs mounted in view of the engineer or driver, and means connecting each pair in series with one of the engine spark plugs together with a shield member having a series of apertures, each arranged to register with one pair of said electrodes, said shield being movable out of registration with said electrodes, and a series of contact plates associated with the shield in positions to engage and shunt the respective pairs of electrodes when the shield is so shifted.
12. In combination with a plurality of electric circuits having a common return or ground connection, a testing device comprising an insulated mount carrying a series of visible indicators, each connected in series with one of said circuits, an electric contact associated with each indicator and connected to its circuit, and a grounded contact member formed to engage simultaneously a definite number, but not all, of said indicator contacts and movable at will for thus grounding the circuits in different groups for locating faults.
13. In combination with a plurality of electric circuits, a testing device comprising a series of visible indicators, each connected in series with one of said circuits, a cover member or shield having a series of apertures through each of which one of said indicators is visible, the shield being movable for shifting said apertures out of registration with the indicators, an electric contact associated with each indicator and connected to its circuit, a series of contacts fixed in the shield, and each positioned to

maintain electric connection with one of said indicator contacts throughout the range of movement of said shield, together with a grounded contact member formed to engage simultaneously a definite number, but not all of said contacts on the shield and movable relatively thereto for selectively ground-

ing the circuits in different groups for detecting faults therein.

In testimony whereof, I have hereunto set my hand at Chicago, Illinois, this 7th day of February, 1919.

HENNING R. SJOLANDER.
